(57) **CLAIM**

The ornamental design for a load mounting system, as
shown and described.

DESCRIPTION

FIG. 1 is a top right rear isometric view of a first embodiment of a load mounting system showing the new design; FIG. 2 is a top left front isometric view thereof; FIG. 3 is a rear elevational view thereof; FIG. 4 is a right elevational side view thereof, relative to FIG. 3, with the left elevational side being a mirror image; FIG. 5 is a front elevational view thereof; FIG. 6 is a bottom plan view thereof; FIG. 7 is a top plan view thereof; FIG. 8 is an exploded top left rear isometric view thereof; FIG. 9 is a top right rear isometric view thereof in first state of use; and FIG. 10 is a top right rear isometric view thereof in a second state of use. FIG. 11 is a top right rear isometric view of a second embodiment of a load mounting system showing the new design; FIG. 12 is a top left front isometric view thereof; FIG. 13 is a rear elevational view thereof; FIG. 14 is a right elevational side view thereof, relative to FIG. 13, with the left elevational side being a mirror image; FIG. 15 is a front elevational view thereof; FIG. 16 is a bottom plan view thereof; FIG. 17 is a top plan view thereof; FIG. 18 is an exploded top left rear isometric view thereof; FIG. 19 is a top right rear isometric view thereof in first state of use; and, FIG. 20 is a top right rear isometric view thereof in a second state of use.

The broken lines shown in the figures depict portions of the load mounting system which form no part of the claimed design. The electronic device depicted in broken lines in
